[57] ABSTRACT

An interlocking modular building system which utilizes a plurality of spaced, vertically stacked modules to form columns for the building. The module columns are connected to a floor system comprising a plurality of beams and floor elements. In the preferred embodiment, the vertically stacked modules each have a generally "U" shape in plan view and are notched to receive one or more beams. The beams are connected at at least two points to one or two of the modules. A third connection for each beam is made to a module or to another beam. The floor elements are also connected at at least three points, two of which are to the modules or beams or to a combination thereof. The third connection for each floor element is made to a module, beam or another floor element. The resulting interlocking arrangement of the modules, beams and floor elements produces a stable three dimensional space frame.

INTERLOCKED MODULAR BUILDING SYSTEM

This is a continuation of application Ser. No. 121,465 filed Mar. 5, 1971, now abandoned.

BACKGROUND OF THE INVENTION

This invention relates to modular building systems in general and, more particularly, to a modular building system in which the column forming modules, beams and floor elements are structurally interlocked to produce a three-dimensional space frame.

In the past, various types of modular building systems have been proposed to simplify building construction techniques with a concomitant reduction in building costs. The use of prefabricated, pre-finished, room-size modules for bathrooms, kitchens, utility rooms and the like was suggested at least as early as 1939 in U.S. Pat. No. 2,168,725, issued Aug. 8, 1939 to J. J. Whelan for **BUILDING CONSTRUCTION**. The Whelan patent describes a multi-story building construction in which various types of modules are vertically stacked to form a shaft. After all of the modules are in place, concrete is poured through the tubes in each of the modules filling all of the spaces therein. The resulting enclosed concrete, load-bearing column directly supports the floors and roof only for gravity loads. Since the Whelan building construction does not provide a frame action to resist racking loads, it is impractical for use in current buildings.

Other pre-fabricated, pre-finished building systems have employed full, large size room units which are assembled in longitudinal or transverse relationship and/or stacked in superposed relationship. One typical example of such a building system is illustrated in U.S. Pat. No. 3,292,327, issued Dec. 20, 1966 to Van Der Lely for **PLURAL STORY BUILDING COMPRISING SUPERIMPOSED BOX-SHAPED DWELLING UNIT**. The large or full size room building system shown in Van Der Lely and other similar patents has some advantages, but, the disadvantages of the system outweigh its advantages. For example, the physical size of the box-shape dwelling units precludes the use of highway transportation for moving the dwelling units from the manufacturing site to the construction site. In addition, the system is generally unsuitable for highrise construction.

It is accordingly, a general object of the present invention to provide a modular building system which eliminates the major problems of the prior art systems.

It is specific object of the present invention to provide an interlocking modular building system which produces a three-dimensional space frame through the repetitive use of fixedly inter-connected structural elements, including modules, fixedly inter-connected structural elements, including beams and floor elements.

It is another object of the invention to provide a modular building system which allows the architect wide latitude in designing and implementing various types of floor plans.

It is still another object of the present invention to provide an interlocking modular building system which employs easily constructed and, if desired, pre-cast modules in conjunction with conventional pre-cast beams and floor elements.

It is a feature of the present invention that various types of buildings can be constructed using the same basic modular system components of modules, beams and floor elements.

It is another feature of the invention that a building constructed with the interlocking modular building system costs less per square foot in terms of actual building construction costs than a comparable building constructed by conventional techniques.

These objects and other objects and features of the present invention will best be understood from a detailed description of a preferred embodiment thereof, selected for purposes of illustration and shown in the accompanying drawings in which:

FIG. 1 is a perspective view in partial cut-away illustrating the interlocking, stacked, vertical modules, beams and floor elements of the modular buildings system of the present invention;

FIG. 2 is a view in cross-section taken along line 2-2 in FIG. 1;

FIG. 2A is an enlarged detailed view in side elevation showing the connection of two of the horizontal beams depicted in FIG. 1;

FIG. 3 is a plan view of a portion of one building floor configuration using the module shown in FIG. 1;

FIG. 4 is an enlarged plan view of one of the room units depicted in FIG. 3.

FIG. 5 is a perspective view in partial cut-away of another embodiment of the interlocking, vertically stacked modules;

FIG. 6 is a view in cross-section taken along lines 6-6 in FIG. 5;

FIG. 7 is a view in cross-section taken along lines 7-7 in FIG. 5;

FIGS. 8a and 8b are enlarged views in front elevation showing two systems for interconnecting the modules, beams and floor elements;

FIG. 9 is a view in perspective of a multi-story building incorporating the modules illustrated in FIG. 5;

FIG. 10 is a view in perspective and partial cut-away of still another embodiment of the interlocking, vertically spaced modules;

FIG. 11 is a view in cross-section taken along lines 11-11 in FIG. 10;

FIG. 12 is a plan view of one floor of a building showing the use of a combination of different types of modules;

FIG. 13 is a side elevation of two connected modules illustrating another embodiment of the modules; and,

FIG. 14 is a plan view of the modules depicted in FIG. 13.

Turning now to the drawings, FIG. 1 illustrates in perspective and partial cut-away view the interlocking arrangement of the components of the modular building system of the present invention. The system used only three basic types of structural element or components; a module 10, a beam 12 and a floor element 14. These three basic components are assembled together at the building site in an interlocking, repetitive pattern to produce a three-dimensional space frame for single and multi-story buildings.

The module 10 can be constructed from a number of materials including concrete, brick and mortar, wood, metal and plastic. Preferably, the modules 10 are formed from pre-cast concrete which can be poured at a remote location with the finished module being trucked to the construction site, or poured at the construction site itself. The size of the modules when viewed in plan can vary over a wide range depending upon the particular application for the module. For example, the two modules illustrated in FIG. 1 can range

in size from approximately 3 feet square to 12 feet square. However, if the module must be shipped by highway, an 8 foot limitation is desirable in order to avoid the problems associated with trucking extra wide loads. The vertical height of the module can vary from approximately 8 feet up to the general maximum story height of 13 feet for a single story module. For a single, multiple story module, the vertical height and base dimensions will, of course, be greater. Since the modules can be pre-cast or manufactured at a remote location, pre-finishing of the module and installation of suitable equipment, such as, the components of a bathroom or kitchen, are quite feasible and offer a cost saving over corresponding on-site work.

The interlocking modular building system of the present invention can best be understood by looking at FIGS. 1 through 4 which illustrate the use of one embodiment of the module 10 together with the beams and floor elements 12 and 14, respectively, to construct a multi-story, three-dimensional space frame. In the embodiment shown in FIGS. 1 through 4, the module 10 comprises a pre-cast concrete unit having a U-shape in plan view with two vertical side walls 16 and 18, a back wall 20 and a floor 22. Although the module 10 is shown with three sides, 16, 18, and 20, three sides are not absolutely required. Conceptually, the space frame can be constructed with a two sided module, but three sides are preferred as shown in FIG. 1. The module floor 22 can be cast in place, as illustrated in FIG. 1, or omitted from the module. In the latter situation, a horizontal surface is formed within the module by an extension of one or more of the floor elements 14. In any event, each such module preferably includes at least two vertically extending, angularly interconnected walls.

The upper forward edges of the side walls 16 and 18 are cut-away to form step notches or recesses 24 and 26, respectively. Alternatively, the step notches 24 and 26 can be formed during the casting of the module. Each step notch 24 and 26 has a horizontal and vertical dimension which corresponds to the horizontal and vertical dimensions of the beams 12. Thus, when the beams are placed on the step notches 24 and 26, as shown in FIGS. 1 and 2, the upper surface of each beam will be coplanar with the upper surface of the vertical walls 16, 18, and 20 and with the front surfaces of the side walls 16 and 18. Although this particular arrangement is desirable, it should be understood that from the standpoint of the resulting structure, the lower portion of each module side wall 16 and 18 can be notched to accommodate the beam 12. Other configurations for the module notching and beam positioning will be discussed below in connection with FIGS. 5, 10, 13 and 14.

The two beams 12 illustrated in FIG. 1 are connected to each other by means of metal tie plates 28 and 30 as shown in FIG. 2A. The metal tie plates are cast into the ends of the beam and are secured therein by means of tie wires 32 and 34, respectively. After the beams are positioned in the module notches 24 and 26, a field weld 36 is made to join the two tie plates 28 and 30 together. While other connecting systems, such as drilled fastening plates and bolts can be used to connect the two beams together, the use of field welded tie plates eliminates the need for accurate drilling and positioning of the connecting means.

5 Each beam 12 is also connected to the floor elements 14. Looking at FIGS. 1 and 2, a metal plate for insert 38 is mounted within and flush to the surface of the pre-cast beam. A corresponding metal insert 40 is mounted on the stem 42 of the double Tee floor element 14. Once the beams 12 have been positioned within the appropriate notches 24 and 26 on the underlying module and the upper module is positioned there-over, a field weld is made between an angle bracket 44 and the corresponding metal inserts 38 and 40. Similar metal inserts and angle brackets are used to secure the other stem 42a of the double Tee floor element 14. These inserts and brackets can best be seen in FIG. 2 and are identified by the same numerals with a small letter *a* added thereafter.

10 The same type of fastening system is also used to secure the ends of the floor element stems 42 and 42a to the back wall of the module. Looking at FIG. 2, a metal insert 46 is embedded in the pre-cast stem 42a of floor element 14. Another plate 48 is mounted within the inside back wall of the module. Angle bracket 50 is field welded to the metal inserts 46 and 48 after the dry assembly of the modules, beams and floor elements.

15 After the dry assembly of the vertically stacked modules 10 and the interlocking beams and floor elements, it is desirable to clamp the modules and beams together by means other than gravity. For this purpose, and by way of illustration only, post tensioning rods 52 are shown representatively in FIGS. 1 and 2. The corresponding post tensioning components, such as, bearing plates and nuts have been omitted for purposes of clarity and no specific detail has been shown on the post-tensioning rods. Since such post tensioning systems are well-known in the art, these details are not needed for an understanding of the present invention. Furthermore, it will be appreciated that other systems besides post tensioning can be employed to connect the modules together.

structed with 8 foot modules and a spacing between the exterior walls of approximately 37 to 38 feet. This arrangement leaves two 16 foot deep apartment units and a 5 foot wide corridor 62. Looking at the enlarge plan view of a typical apartment unit 58 show in FIG. 4, the unit comprises a living room-kitchen area 64, a bedroom 66 and the previously mentioned bathroom 56. Representative dimensions for the living room-kitchen area are: a length of 16 feet from the corridor to the exterior wall 60 and a width of 13 feet 6 inches. The bedroom 66 has a width of 10 feet 6 inches and a depth including the closet space of 16 feet. Normally, pipe chase 68 is provided on the interior side of the module 10 and, preferably, the pre-case module is prefinished with the major bathroom components installed before the module is positioned in place at the construction site.

It will be appreciated from the preceding description of the interlocking modular building system and the representative floor plans shown in FIGS. 3 and 4 that the system provides considerable flexibility in both floor plans and types of buildings. For example, the system can be used to construct multiple occupancy dwellings including apartment buildings, hotels and motels all of which rerequire numerous service modules e.g. bathrooms and kitchens. The modular system is also well suited for any type of building construction which requires large, open bays. Since the system is not limited to the specific module configuration shown in FIG. 1, additional flexibility can be achieved by using a combination of different types of modules. One such combination of different types of modules is illustrated in FIG. 12 and will be discussed in detail after a description of the two additional types of modules depicted in FIGS. 5 and 10.

Referring to FIGS. 5 through 9, and in particular, FIG. 5, there is shown another embodiment of the module 10. Where possible, the same reference numerals have been used in FIGS. 5 through 9 to identify the same components previously discussed in connection with FIGS. 1 through 4. The module 10 again has a generally U shape in plan view with side walls 16 and 18 and a back wall 20. If the optional module floor 22 is used, it is generally pre-cast with the module. The side walls 16 and 18 are cut-away or cast with a full notch or recess 70 and 72, respectively. The position of the full notches 70 and 72 along the side walls can be varied to accommodate different building floor plans. The width and depth of the two notches corresponds to the width and height of the beams 12 to provide a flush surface when the beams are assembled in interlocking relationship with the modules as best shown in FIG. 6. Again, depending upon module height and the desired configuration, the notches 70 and 72 can be located in the lower portion of each module.

The fastening system for securing the floor elements 14 to the beams is substantially the same as previously described. Thus looking at FIGS. 5 and 6, each beam 12 is provided with a metal insert 38 and a corresponding metal insert 40 is mounted on the single Tee stem 42. After dry assembly of the interlocking modules, beams and floor elements at the construction site, a field weld is made between the angle bracket 44 and the metal plates inserts 38 and 40.

A similar fastening system is also used to connect the floor elements 14 to the module. Each single Tee stem 42 is provided with a metal insert 46 (FIG. 6). A corre-

sponding metal insert 48 is located on the forward edge of each of the side walls. The angle bracket 50 is field welded to the metal plates 46 and 48 after dry assembly of the structural components. If desired, a concrete topping 54 can be poured over the floor elements 14 to provide a smooth and continuous surface. Preferably, the concrete topping surface should be co-planar with the surface of the module floor 22. If the module 10 is formed from pre-cast concrete, optional metal tie rods 74 can be secured within the pre-cast concrete to provide a connection between the concrete topping 54 and the module 10.

FIGS. 8a and 8b illustrate in enlarged form two methods for securing the single Tee stem 42 to the side walls 16 and 18 of the module. FIG. 8a shows the method previously described in connection with FIGS. 5 and 6 in which the beam and Tee stem metal inserts 38 and 40, respectively, are field welded to an angle bracket 44. If post-tensioning of the vertically stacked modules is employed, as shown for illustrative purposes in FIGS. 5 through 8, then the stem 42 of the floor element can be clamped between a portion of the side walls and the beams. FIG. 8b illustrates this arrangement and shows the side walls 18 with an undercut area 76 that accommodates a portion of the Tee stem 42. When the upper and lower modules are clamped together by means of the post-tensioning rods 52, the Tee stem 42 will be securely held in place and structurally connected to the module and beam.

FIG. 9 illustrates in perspective view a portion of the multi-story building constructed in accordance with the present invention. It can be seen from FIG. 9 that the interlocking modular building system provides a very flexible building system with the option of obtaining large open bays by using in repetitive sequence the three basic components of modules, beams and floor elements. Where multi-story open areas are desired, as for example, in hotel ballrooms, the floor elements 14 can be omitted from one or more floors.

It has already been mentioned that additional flexibility can be achieved by using a combination of the various types of modules. FIGS. 10 and 11 illustrate a third type of module. The same reference numerals will again be used to identify the same elements described in connection with FIGS. 1 through 4. The module shown in FIG. 10 combines the beam-notch arrangement of the modules depicted in FIGS. 1 and 5. The module 10 has two step notches 24 and 26 located at the upper forward edge of the side walls 16 and 18, respectively. The height and depth of the step notches 24 and 26 correspond to the width and height of the beams 12, as best seen in FIG. 11. Two full notches 70 and 72 are also provided in the side walls 61 and 18, respectively. However, in this case, the location of the full notches 70 and 72 is different from the location of the same notches shown in FIG. 5. The beams 12 are positioned within the step notches 24 and 26 and the full notches 70 and 72 as best seen in FIG. 11.

The beams 12 support a floor system formed a plurality of hollow core, slab floor elements 14. The floor elements 14 are secured to the beams by means of the plate and welded angle bracket system previously described in connection with the FIGS. 1 and 5. It should be noted that in this arrangement, the metal insert plate 40 is positioned on the under surface of the floor slab 14.

Each module is undercut on the forward portion of the side walls 16 and 18 to accommodate the combined thickness of the floor slab 14 and the concrete topping 54. It can be seen from an inspection of FIG. 11 that when the vertically stacked modules are connected together by suitable means, such as, the previously described post-tensioning system, some of the floor elements 14 will be clamped between the module side walls and the underlying beam. The other floor elements 14 are connected to the beams by means of the welded angle bracket system. Thus, after post-tensioning and field welding of the angle brackets, the interlocked modules, beams and floor elements provide the desired three-dimensional space frame.

FIG. 12 illustrates in plan view a building structure that incorporates three different types of modules 10. The right hand row of modules are of the type shown in FIGS. 1 through 4 with step notch at the forward end at each of the side walls 16 and 18. Two beams 12 are used to span the three right hand modules. The beams are connected together in the right hand center module in the manner shown in FIG. 2a. The center vertical row, as viewed in FIG. 12, uses the module configuration illustrated in FIGS. 5, 6, and 7. Again, two beams 12 are used to span the three modules and the two beams are connected together in the same manner as previously described. The left hand set of modules is similar in configuration to the module structure shown in FIGS. 10 and 11 with the omission of the step notches 24 and 26. Two beams are likewise used to span the distances between the modules and are connected together in the same manner.

Single Tee floor elements 14 span the distance between the right hand and center beams, as viewed in FIG. 12. The floor elements are secured to the beams by the angle brackets system previously described. The extended portions of the Tee stems are also connected to the side of the module by the plate and angle bracket system with only the angle bracket 50 being shown in FIG. 12. The left hand set of floor elements 14 span the distance between the center beam and the left hand beams are cantilevered outwardly to the left as viewed in FIG. 12 from the left hand set of beams. Here again, the single Tee floor elements 14 are connected to the two beams and to the modules. Typical dimensions for the building shown in FIG. 12 are as follows: length, 120 feet; width, 80 feet; distance between beams measured along the long dimension of the building, 48 feet; module size, 8 feet; and, length of the cantilever, 12 feet.

The flexibility of the interlocking modular building system of the present invention is further demonstrated by still another module configuration shown in FIGS. 13 and 14. In many types of multi-occupancy dwellings, such as hotels and apartment houses, it is desirable to have one or more relatively narrow, centrally located corridors to provide access to the individual dwelling units. The vertically stacked modules shown in side elevation in FIG. 13 and in plan view in FIG. 14 greatly simplify this type of construction. Looking at FIGS. 13 and 14, the modules 10 are similar to the previously discussed module depicted in FIG. 5. Where possible the same reference numerals have been used in FIGS. 13 and 14 to identify similar elements. Each module has a generally U shape in plan view with two side walls 16 and 18, a back wall 20 and an optional floor 22. Step notches 70 and 72 are cut into or formed in the side

walls 16 and 18, respectively. The one difference between the module illustrated in FIG. 5 and that shown in FIGS. 13 and 14 is a planar floor projection or extension 78 which extends outwardly from the back wall 20 and, preferably, is co-planar with the module floor 22. If the module is formed from pre-cast concrete, the module with its floor 22 and extension 78 can be cast as a monolithic unit. The two sets of vertically stacked modules are arranged with the extensions 78 in abutting relationship. The extensions are connected together by means of a metal plate 80 that is field welded to corresponding metal inserts 82 in each of the extensions.

From a structural standpoint, the two extensions 78 correspond to the previously discussed floor element 14. The resulting interlocked module, beam and "floor" or extension elements form a three-dimensional space frame. By repeating the paired module arrangement shown in FIGS. 13 and 14, it is possible to form a modular core for a multi-dwelling building which provides the necessary resistance to lateral loads. This modular core constitutes the primary structural system for the building. The exterior system can be constructed in a variety of conventional ways with in-fill slabs being used to form a floor system between the beams 12 and the exterior walls (not shown).

It will be appreciated from the preceding discussion that the interlocking modular building system of the present invention can be used for all or only a portion of a building. In the latter case, the system provides the necessary three-dimensional space frame for the building.

Looking specifically at FIG. 13, the extensions 78 and the facing surfaces of the module back walls 20 define a corridor. Typical dimensions for this particular configuration are as follows: module floor dimension, 8 square feet; module height, 8 to 13 feet; module extension length, 3 feet. Thus for an apartment or hotel construction, the two modules shown in FIGS. 13 and 14 provide a 6 foot wide corridor.

For multi-dwelling units, the modules shown in FIGS. 13 and 14 normally would be pre-fabricated as service modules i.e., kitchens, or bathrooms. The adjoining dwelling unit bathroom or kitchen is constructed at the building site in abutting relation with one of the module side walls 16 or 18. This configuration then permits a back-to-back arrangement with common water supply, waste, drain and vent lines.

Having described in detail a number of embodiments of the modules 10 and the corresponding interlocking relationship among the modules, beams, and floor elements, certain generalizations can be made about the interlocking module building system of the present invention. For example, although the preferred module embodiment has a generally U shape in plan view with three sides, the system can be constructed with a module having at least two connected vertical sides. Each of the spaced, horizontally, extending beams 12 is connected at at least three points. Two to the points are to one or two of the modules 10 while the third point is to a module or beam. Similarly, the longitudinal, horizontally extending floor elements 14 are each connected at at least three points of which two of the points are to one of the modules or to two of the modules or to a combination of one of the modules and one of the beams, or to two of the beams. The third point of connection for each floor element is to one of the

modules or beams or to another floor element. Given these general requirements, the three basic components of the interlocking modular building system can be arranged in a variety of ways to accommodate the architect's floor plans. In each instance, however, the 5 modules, beams and floor elements are connected together as defined above to form a threedimension space frame.

It will be apparent to those skilled in the art that numerous modifications can be made to the interlocking 10 modular building system of the present invention without departing from the scope of the invention as set forth in the appended claims.

What we claim and desire to protect by Letters Patent of the United States is:

1. A modular building structure, comprising:

a plurality of fixedly interconnected structural elements, aligned connecting means on each of said structural elements fixedly connecting said structural elements together, said structural elements including vertically extending modules, horizontally extending beams, and horizontally extending floor elements, means fixedly connecting each of said beams and floor elements at at least spaced 20 points thereon to at least another one of said structural elements, 25

said modules each being substantially U-shaped in horizontal cross section and including a pair of vertically extending side walls and a vertically extending back wall connected to the side walls, said side 30 walls each having an upper marginal edge surface and a lower portion with at least one beam receiving recess in each of said upper marginal edge surfaces, 35

said beam receiving recesses being located in the front marginal edges or corners of the upper edge surfaces of the side walls and comprising step recesses having a depth and width corresponding to the cross sectional thickness of a beam so that a beam positioned in a recess is flush with the edge 40 surfaces of the modules,

at least some of said beams received in said recesses and each fixedly connected at at least two spaced points thereon to said modules, and each fixedly connected at a third point thereon to another one of said structural elements, 45

said floor elements each being elongate and substantially rectangularly shaped and supported on said beams in a horizontal position, each of said floor elements being fixedly connected at at least two spaced points thereon to at least one other of said structural elements, and fixedly connected at a third point thereon to another one of said structural elements, 50

adjacent connecting means on said structural elements being aligned and operatively secured together to fixedly secure said beams, modules, and floor elements together to define a three-dimensional space frame which resists horizontal and vertical loads.

2. A modular building structure, comprising:

a plurality of fixedly interconnected structural elements, aligned connecting means on each of said structural elements fixedly connecting said structural elements together, said structural elements including vertically extending modules, horizontally extending beams, and horizontally extending

floor elements, means fixedly connecting each of said beams and floor elements at at least three spaced points thereon to at least another one of said structural elements,

said modules each being substantially U-shaped in horizontal cross section and including a pair of vertically extending side walls and a vertically extending back wall connected to the side walls, said side walls each having an upper marginal edge surface and a lower portion with at least one beam receiving recess in each of said upper marginal edge surfaces,

said beam receiving recesses being located between opposite ends of the upper marginal edge surface of the side walls and comprising full recesses having a depth and width corresponding to the cross sectional thickness of a beam so that a beam positioned in a recess is flush with the upper marginal edge surface of the modules,

at least some of said beams received in said recesses and each fixedly connected at at least two spaced points thereon to said modules, and each fixedly connected at a third point thereon to another one of said structural elements,

said floor elements each being elongate and substantially rectangularly shaped and supported on said beams in a horizontal position, each of said floor elements being fixedly connected at at least two spaced points thereon to at least one other of said structural elements, and fixedly connected at a third point thereon to another one of said structural elements,

adjacent connecting means on said structural elements being aligned and operatively secured together to fixedly secure said beams, modules, and floor elements together to define a three-dimensional space frame which resists horizontal and vertical loads.

3. A modular building structure as in claim 2, wherein at least one beam extends between the side walls of one module and is received in the recesses in said side walls.

4. A modular building structure as in claim 2, wherein each beam is connected at two spaced points thereon to one module and at a third point to another module.

5. A modular building structure as in claim 2, wherein each beam is connected at two spaced points thereon to one module and at a third point to another beam.

6. A modular building structure as in claim 2, wherein each beam is connected at two spaced points thereon to two separate modules and at a third point to another module.

7. A modular building structure as in claim 2, wherein each beam is connected at two spaced points thereon to two separate modules and at a third point to another beam.

8. A modular building structure as in claim 2, wherein each floor element is connected at two spaced points thereon to one of the modules and at a third point thereon to another module.

9. A modular building structure as in claim 2, wherein each floor element is connected at two spaced points thereon to two separate modules and at a third point thereon to another module.

10. A modular building structure as in claim 2, wherein each floor element is connected at two spaced points thereon to a module and a beam and at a third point thereon to another floor element.

11. A modular building structure, comprising:
a plurality of fixedly interconnected structural elements, aligned connecting means on each of said structural elements fixedly connecting said structural elements together, said structural elements including vertically extending modules, horizontally extending beams, and horizontally extending floor elements, means fixedly connecting each of said beams and floor elements at at least three spaced points thereon to at least another one of said structural elements.

said modules each being substantially U-shaped in cross section and including a pair of vertically extending side walls and a vertically extending back wall connected to the side walls, said side walls each having an upper marginal edge surface and a lower portion with at least one beam receiving recess in each of said upper marginal edge surfaces, a plurality of said modules being connected together in superposed, vertically stacked relationship to form a vertical column, said structural including a plurality of said columns in spaced apart relationship with said columns each comprising a pair of adjacent, vertical stacks of U-shaped modules, with the back walls of the modules in one stack adjacent the back elements of the modules in the adjacent stack, a horizontal projection on the back wall of each module extending toward the back wall of an adjacent module, and means connecting together the extensions on adjacent pairs of modules, at least some of said beams received in said recesses and each fixedly connected at at least two spaced points thereon to said modules, and each fixedly connected at a third point thereon to another one of said structural elements,

said floor elements each being elongate and substantially rectangularly shaped and supported on said beams in a horizontal position, each of said floor elements being fixedly connected at at least two spaced points thereon to at least one other of said structural elements, and fixedly connected at a third point thereon to another one of said structural elements,

adjacent connecting means on said structural elements being aligned and operatively secured together to fixedly secure said beams, modules, and floor elements together to define a three-dimensional space frame which resists horizontal and vertical loads.

12. A modular building structure, comprising:
a plurality of fixedly interconnected structural elements, aligned connecting means on each of said structural elements fixedly connecting said structural elements together, said structural elements including vertically extending modules, horizontally extending beams, and horizontally extending floor elements, means fixedly connecting each of said beams and floor elements at at least three spaced points thereon to at least another one of said structural elements,

said modules each including at least two vertically extending, angularly interconnected walls each having an upper marginal edge surface and a lower

portion with at least one beam receiving recess in each of said upper marginal edge surfaces, at least some of said beams received in said recesses and each fixedly connected at at least two spaced points thereon to said modules, and each fixedly connected at a third point thereon to another one of said structural elements,

said floor elements each being elongate and substantially rectangularly shaped and supported on said beams in a horizontal position, each of said floor elements being fixedly connected at at least two spaced points thereon to at least one other of said structural elements, and fixedly connected at a third point thereon to another one of said structural elements,

adjacent connecting means on said structural elements comprising metallic members cast into said modules, beams and floor elements with portions thereof exposed, said exposed portions of adjacent, aligned connecting means welded together, to fixedly secure said beams, modules, and floor elements together to define a three-dimensional space frame which resists horizontal and vertical loads.

13. A modular building structure, comprising:
a plurality of fixedly interconnected structural elements, aligned connecting means on each of said structural elements fixedly connecting said structural elements together, said structural elements including vertically extending, precast concrete modules, horizontally extending precast concrete beams, and horizontally extending precast floor elements, means fixedly connecting each of said beams and floor elements at at least three spaced points thereon to at least another one of said structural elements,

said modules being substantially U-shaped in horizontal cross section with vertically extending, angularly interconnected walls each having an upper marginal edge surface and a lower portion with at least one beam receiving recess in each of said upper marginal edge surfaces,

at least some of said beams received in said recesses and each fixedly connected at at least two spaced points thereon to said modules, and each fixedly connected at a third point thereon to another one of said structural elements,

said floor elements each being elongate and substantially rectangularly shaped and supported on said beams in a horizontal position, each of said floor elements being fixedly connected at at least two spaced points thereon to at least one other of said structural elements, and fixedly connected at a third point thereon to another one of said structural elements,

adjacent connecting means on said structural elements being aligned and operatively secured together to fixedly secure said beams, modules, and floor elements together to define a three-dimensional space frame which resists horizontal and vertical loads.

14. A modular building structure as in claim 13, wherein a poured in situ concrete topping is on top of said floor elements.

15. A modular building structure as in claim 14, wherein metal tie rods are cast into said modules and have exposed portions extending into said poured in situ topping to secure the topping to the modules.

16. A modular building structure, comprising a plurality of fixedly interconnected, vertically extending modules, horizontally extending beams and horizontally extending floor elements, said modules each comprising precast concrete and each substantially U-shaped in horizontal cross section and including a back wall and a pair of spaced apart side walls having upper edge surfaces, aligned notches in the front, upper corners of the side walls of each module, a pair of axially aligned, horizontal, end-to-end beams received in the notches in each module in perpendicular relationship to the plane of the side walls and with adjacent ends of the pair of beams positioned between the side walls of the associated module, beam connecting means on the adjacent ends of the pair of beams, means connecting the beam connecting means together to rigidly connect the beams to one another, a plurality of horizontal floor elements supported on the beams, each of said floor elements having a pair of spaced apart, parallel, longitudinally extending, downwardly projecting ribs on the underside thereof, said ribs supported on the tops of said beams, floor element and beam connecting means on said ribs and on adjacent portions of said beams, means connecting the floor element and beam connecting means together to rigidly secure the floor elements to the beams, floor element and module connecting means on the floor elements and on adjacent portions of the modules, and means connecting the floor element and module connecting means together to rigidly connect the floor elements to the modules, to define a three-dimensional space frame which resists horizontal and vertical loads.

17. A modular building structure, comprising a plurality of fixedly interconnected, vertically extending modules, horizontal beams and horizontal floor elements, said modules each comprising precast concrete and each substantially U-shaped in horizontal cross section and including a back wall and a pair of spaced apart side walls having upper edge surfaces, aligned notches in the upper edge surfaces of the side walls between opposite ends of the upper edge surfaces, a horizontal beam received in the notches and extending between and perpendicular to the side walls of the modules, a plurality of horizontal floor elements supported on the beam, a longitudinally extending, downwardly projecting rib on the underside of each floor element, said ribs supported on top of the beams, floor element and beam connecting means on the rib of each floor element and on an adjacent portion of the beams, means connecting the connecting means together to rigidly connect the floor elements to the beams, floor element and module connecting means on the ribs of the floor elements and on adjacent portions of the modules, and means rigidly connecting the floor element and module connecting means together to rigidly connect the floor elements to the modules to define a three-dimensional space frame which resists horizontal and vertical loads.

18. A modular building structure, comprising a plurality of fixedly interconnected, vertically extending modules, horizontal beams and horizontal floor elements, said modules each comprising precast concrete and each substantially U-shaped in horizontal cross section and including a back wall and a pair of spaced apart side walls having upper edge surfaces, aligned notches in the upper edge surfaces of the side walls between opposite ends of the upper edge surfaces, a horizontal beam received in the notches and extending be-

tween and perpendicular to the side walls of the modules, a plurality of horizontal floor elements supported on the beams, a longitudinally extending, downwardly projecting rib on the underside of each floor element, 5 said ribs supported on top of the beams, floor element and beam connecting means on the rib of each floor element and on an adjacent portion of the beams, means connecting the connecting means together to rigidly connect the floor elements to the beams, each module 10 having an undercut portion in a front, lower portion thereof defining a downwardly facing shoulder, and at least one floor element having an end portion thereof received in said undercut portion and clamped between said shoulder and a beam spaced vertically below said 15 shoulder, to define a three-dimensional space frame which resists horizontal and vertical loads.

19. A modular building structure as in claim 18, wherein vertically extending, elongate tie bolts extend through aligned vertical openings in said modules, 20 beams and floor elements to securely clamp the modules, beams and floor elements together.

20. A modular building structure comprising a plurality of fixedly interconnected, vertically extending modules, horizontally extending beams and horizontally extending floor elements, said modules each comprising precast concrete and each substantially U-shaped in horizontal cross-section and including a back wall and a pair of spaced apart side walls having upper edge surfaces, a pair of spaced apart notches in each upper edge 25 surface with the notches in one side wall in alignment with the notches in the other side wall, an undercut portion in a lower front corner of each side wall defining a downwardly facing shoulder in each side wall, horizontal beams received in the notches in the side 30 walls, a plurality of substantially rectangular, flat floor elements supported on top of said beams, at least one floor element having an end portion thereof received in said undercut portion and clamped between said shoulder and an underlying beam, beam and floor element connecting means on the underside of the floor elements and on adjacent aligned portions of the beams, and means rigidly connecting the aligned connecting means together to rigidly secure the floor elements to the beams, to define a three dimensional space frame 35 which resists horizontal and vertical loads.

21. A modular building structure, comprising a plurality of fixedly interconnected, vertically extending modules, horizontally extending beams and horizontally extending floor elements, said modules each comprising precast concrete and each substantially U-shaped in horizontal cross-section and including a back wall, a horizontal projection extending rearwardly from the back wall and a pair of spaced apart side walls having upper edge surfaces, aligned notches in the front, 40 upper corners of side walls of each module, said modules arranged in pairs in back-to-back relationship with the horizontal projections on adjacent modules in alignment with one another, module connecting means on the horizontal projections, means connecting the module connecting means together to rigidly secure the modules to one another, a pair of axially aligned, horizontal, end-to-end beams received in the notches in each module in perpendicular relationship to the side walls and with adjacent ends of the pair of beams positioned between the side walls of the associated module, beam connecting means on the adjacent ends of the 45 pair of beams, means connecting the beam connecting

means together to rigidly connect the beams to one another, a plurality of horizontal floor elements supported on the beams, each of said floor elements having a pair of spaced apart, parallel, longitudinally extending, downwardly projecting ribs on the underside thereof, said ribs supported on the tops of said beams, floor element and beam connecting means on said ribs and an adjacent portion of said beams, means connecting the floor element and beam connecting means to-

5

gether to rigidly secure the floor elements to the beams, floor element and module connecting means on the floor elements and on adjacent portions of the modules, and means connecting the floor element and module connecting means together to rigidly connect the floor elements to the modules, to define a three-dimensional space frame which resists horizontal and vertical loads.
